UNITED STATES PATENT OFFICE

HOLGER BJORNWALD, OF NEW YORK, N. Y.

BELT RETAINER

Refiled for application Serial No. 65,754, filed October 30, 1925. This application filed June 27, 1930. Serial No. 464,186.

This invention relates to improvements in belt retainers and constitutes a refiling of application, Serial No. 65,754, filed October 30, 1925.

5 Belt-buckles frequently "creep" upwardly above the top of the trousers to which they are attached at the junction of the flaps thereof, the supporting function of the belt being thus much impaired, and it is the object of this invention to provide a device which will prevent this upward "creeping" and securely and firmly hold a belt-buckle in its proper place at the top of the trousers, and which, furthermore, may be readily, 15 quickly and easily mounted on the belt-buckle, preferably, upon the upper rung or bar of the base plate thereof and which will have a rearwardly-extending hook portion readily engageable with and disengageable 20 from the inner end of a button hole usually provided in a pair of trousers for cooperation with a button to fasten the flaps together.

Another object of the invention is to enable a detachable hook member to be pivotally mounted on the conventional belt-buckle and, preferably, to enable said hook member to be readily slipped into the button hole and, furthermore, to provide means combined 30 with said hook member which will be engaged and locked against disengagement from the button hole by the tongue of the conventional belt-buckle.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a front elevation of a conventional belt-buckle having my retaining hook attachment connected thereto;

Fig. 2 is a section on the line 2—2 of Fig. 1, looking in the direction of the arrow;

Fig. 3 is a fragmentary view, showing in 50 plan, the upper edge of a pair of trousers

with the belt-buckle connected thereto by my retaining hook and engaged by the tongue of the buckle;

Fig. 4 is a view, in perspective, of a belt-retaining attachment including the hook 55 mounting and locking parts;

Fig. 5 is a section similar to Fig. 2 indicating a modified form of hook adapted to engage a button; and

Fig. 6 is a perspective view of the button-engaging hook shown in Fig. 5. 60

Referring now to these drawings and particularly to Figs. 1 to 4 thereof, 1 indicates a belt-buckle suitably connected at one end of a belt 2 which is, as shown, supported by 65 straps 3 on the trousers having at the front thereof flaps 4, 4' fastened at their upper ends by the conventional means of a button 5 and button hole 6.

The belt-buckle 1 is usually arranged over 70 the button 5 and button hole 6, and in accordance with my invention, a part of this conventional button hole in the trousers is engaged and the buckle is securely anchored in place to prevent any rising or "creeping" in 75 relation to the trousers. Thus, I pivotally mount on the upper frame part 7 of the buckle 1 so as normally to have a swinging movement inwardly and outwardly, a belt-retaining element 8 embodying a retaining 80 hook-portion 9 adapted to be swung or slipped into engagement with the rear end of the button hole 6 when the buckle is being fastened. When this hook so engaged is suitably locked to the buckle, it will prevent any 85 "creeping" or rising of the belt in relation to the trousers, and will hold the belt and belt buckle from slipping upward over the top edge of the trouser flaps so as to detract from the proper support of the trousers, as well as 90 to become unsightly.

In the preferred embodiment of my invention, the element 8 is provided with a mounting portion 10 having a mouth 11 which may be slipped or sprung over the upper bar 95 7 of the buckle frame so as to cause a locking engagement therewith and to have a swinging or pivotal movement thereon. Said element 8 also has a tongue 12 depending at the side of the buckle opposite to the 100

retaining hook, which tongue 12, is engaged by the tongue 13 of the buckle when the same is passed through the holes in the belt to retain the said element 8 against outward swinging movement and thus to retain the hook in engagement with the button hole to lock the buckle thereto.

In Figs. 5 and 6 I have illustrated a modified form of my invention in which a belt-retaining element 8^a has an upwardly and inwardly-extending hook 9^a bifurcated at its upper end to provide tines or fingers 9^b, 9^c and a slot 9^d intermediate the same to permit engagement with the button 5 instead of with the button hole 6 as in Figs. 1 to 4. In other respects the device is similar to that shown in said Figs. 1 to 4.

Having described my invention, I claim:—

An attachment for belt-buckles embodying a buckle frame and tongue, comprising a strip of metal bent intermediate its ends to provide a pivotal mounting portion adapted to slip over a portion of the buckle frame and to swing pivotally thereon and having at its inner end an inwardly and upwardly-extending hook portion adapted to engage a conventional fastening element of a pair of trousers, said member also being provided at the opposite side of the mounting portion with an integral locking tongue adapted to be engaged by the tongue of the buckle when the same is in fastened position.

In witness whereof, I have signed my name to the foregoing specification.

HÖLGER BJORNWALD.
